AUTOMATIC LEAD PENCIL

Filed March 22, 1930

WITNESS: P. J. Shickey;

UNITED STATES PATENT OFFICE

JOHN A. KIEDROWSKI, OF CHICAGO, ILLINOIS

AUTOMATIC LEAD PENCIL

Application filed March 22, 1930. Serial No. 438,217.

This invention relates to an automatic lead pencil, the general object of the invention being to provide means whereby any one of a number of leads carried by the pencil can be moved to projected position, so that by in-
5 moving the leads of different colors, for instance, the one pencil can be used for writing in different colors.

Another object of the invention is to pro-
10 vide simple means for retracting and pro-
jecting the leads, with means for selecting
the lead which it is desired to write with.

This invention also consists in certain other
15 features of construction and in the combina-
tion and arrangement of the several parts, to
be hereinafter fully described, illustrated in
the accompanying drawing and specifically
pointed out in the appended claims.

In describing the invention in detail, ref-
20 erence will be had to the accompanying draw-
ing wherein like characters denote like or
corresponding parts throughout the several
views, and in which:—

Figure 1 is a longitudinal sectional view
25 through the invention.

Figure 2 is a section on line 2—2 of
Figure 1.

Figure 3 is a section on line 3—3 of
Figure 1.

30 Figure 4 is a section on line 4—4 of
Figure 1.

Figure 5 is a section on line 5—5 of
Figure 1.

Figure 6 is a section on line 6—6 of
35 Figure 1.

Figure 7 is a section on line 7—7 of
Figure 1.

Figure 8 is a sectional view through the
cam collar.

40 Figure 9 is a fragmentary elevation show-
ing the indication marks for the adjustment
of the cam collar to project the lead of the
desired color.

In these views, the numeral 1 indicates the
45 pointed member at the front end of the pen-
cil, which is formed with a reduced rear part
2 and a number of longitudinally extending
bores 3 are formed in said member and its
extension, these bores converging and merg-
50 ing at the end of the member.

A small threaded shaft 4 is located in each
bore and a lead holder 5 is connected with the
front end of each shaft, a spring 6 being con-
nected with the holder and the shaft to pro-
55 vide a resilient connection between the two
parts. The lead is shown at 7.

A pin, provided with a rounded head 8,
passes through each shaft adjacent the front
end thereof, with the head of the pin engag-
ing a longitudinally extending groove 9 in
the wall of the bore so that this pin prevents
60 rotary movement of the shaft and acts to
hold the shaft with the lead in proper posi-
tion in the bore.

A bushing 10 is fastened to the rear end of
the extension 2 by the bolts 11 or the like,
said bushing having a reduced front part
which is formed with a number of openings to
receive the toothed wheels 12, with portions
65 of the wheels projecting from the reduced
part. The wheels are located in different
planes and each wheel is formed with a hub
13 which is rotatably arranged in the bush-
ing and extends through the rear end of the
70 bushing. These hubs are internally threaded
to engage the threads of the shafts so that
when the wheels or gears are turned, the
shafts are moved longitudinally so as to pro-
ject or retract the leads.

A collar 14 is rotatably mounted on the re-
duced part 2 and abuts the shoulder formed
at the junction of said reduced part with the
pointed part 1 and said collar is knurled ex-
ternally and is formed with the cam grooves
80 15 internally.

A sleeve 15 is placed on the reduced part 2
and has a flange 16 at its front end which
abuts the collar and said sleeve has a thread-
ed exterior part which is engaged by the in-
ternal threads at the front end of the tubular
body 17. A sleeve or tube 18 is rotatably ar-
ranged in the body and carries a ring gear
19 at its front end which is adapted to en-
gage with any one of the gears 12. This ring
90 gear has exterior projections 20 which engage
slots 21 in the sleeve or tube 18 so that the
ring gear will rotate with the sleeve and
has limited sliding movement therein. The
rear end of the sleeve 18 is formed with a
95 reduced part 22 which passes through a sleeve
100 23.

23 threaded in the rear end of the body 17, the collar or sleeve 23 acting to hold the sleeve 18 in the body. A cap 24 is pressed on the reduced part 22 so that when the cap is turned, the sleeve 18 and the ring gear will be also turned. This cap is formed with a reduced hollow part 25 which extends into the sleeve 18 and is designed to hold a number of leads. An eraser member 26 is frictionally held by the cap and acts as a cover for the lead compartment.

The reduced part 2 is formed with the longitudinally extending grooves 27, in each of which is placed a bar 28 having its front bent end engaging a cam groove 15 and its rear bent end engaging an annular groove 29 in the ring gear, so that when the cam collar 14 is turned, the bars 28 are moved longitudinally due to the engagement of their bent ends with the cam grooves 15 and thus the ring gear 19 is moved forwardly or rearwardly in the sleeve 18. This ring gear in its forward position, will engage a gear 12 of one of the shafts 4, in its intermediate position, the ring gear will engage another of the gears 12 and in its rear position, will engage the third gear 12. Thus by turning the cam collar 14, the ring gear can be placed in mesh with the gear 12 of the lead which it is desired to retract or project and then by turning the cap 24, the sleeve 18 and the ring gear are turned to impart rotary movement to the gear 12 which is in mesh with the ring gear and this turning movement of the gear 12 will impart longitudinal movement to the shaft 4 which passes through the hub of the gear 12. Thus a lead can be drawn into the device and another lead projected therefrom by first engaging the ring gear with the gear of that shaft which is to be moved and then turning the cap 24 to move the shaft longitudinally. As before stated, by having the leads of different colors, the one pencil can be used for writing in different colors.

The pencil is provided with the usual cap 30 for covering the cap 24 and the eraser 26 and it is also provided with the member 31 for holding the pencil in a pocket or the like. This member 31 is formed with the pointed engaging part 32 for insuring a tight grip on the material of the pocket.

The member 1 may be formed of sections as shown at 1" in Figures 5, 6 and 7 and in this case, a cap 1' is placed over the sections to hold them in position, as shown in Figure 1.

The cam collar 14 is formed with a mark 60 which co-operates with indicia on the pointed part of the device for enabling the collar to be set to cause the operating means to project the desired lead, as shown in Figure 9.

65 It is thought from the foregoing descrip-

tion that the advantages and novel features of the invention will be readily apparent.

It is to be understood that changes may be made in the construction and in the combination and arrangement of the several parts, provided that such changes fall within the scope of the appended claims.

What I claim is:—

1. A pencil of the class described comprising a body having a plurality of bores therein, the bores converging to the front end of the pencil, a threaded shaft in each bore, a lead holder connected with the front end of each shaft, a plurality of gears in the body having threaded bores therein through which the shafts pass, a ring gear in the body, means for adjusting said ring gear to place it in mesh with any desired gear and means for rotating the ring gear to cause the gear with which it engages to move the shaft longitudinally.

2. A pencil of the class described comprising a body having a plurality of forwardly converging bores therein, a threaded shaft in each bore, a lead holder connected with the front end of each shaft, a plurality of gears in the body having threaded bores therein through which the shafts pass, a ring gear in the body, a sleeve rotatably arranged in the body and to which the ring gear is slidably but non-rotatably connected, a cap at the rear end of the body and connected with the sleeve for rotating the same, a cam collar carried by the body, members having projections at their front ends engaging the grooves of the cam collar, the rear ends of said members having projections engaging a groove in the ring gear whereby turning movement of the cam collar will bodily move the ring gear so that said ring gear can be placed in mesh with any one of the gears.

3. A pencil of the class described comprising a body having a plurality of forwardly converging bores therein, a threaded lead carrying shaft in each bore, a plurality of gears in the body having threaded bores through which the shafts pass, said gears being arranged in different planes, a ring gear in the body, means for bodily moving the same to place it in mesh with any one of the gears and means for rotating the ring gear to cause the gear with which it meshes to move a shaft longitudinally.

In testimony whereof I affix my signature.

JOHN A. KIEDROWSKI. 120
